UNITED STATES PATENT OFFICE.

HENRY ROOT, OF PHILADELPHIA, PENNSYLVANIA, ASSIGNOR TO THOMAS DOLAN AND R. WILLIAMS, JR., OF SAME PLACE.

DESIGN FOR KNITTED FABRIC.

Specification forming part of Design No. **11,125**, dated March 25, 1879; application filed February 4, 1879.
[Term of patent $2\frac{1}{2}$ years.]

To all whom it may concern:

Be it known that I, HENRY Root, of Philadelphia, Pennsylvania, have produced or invented a new and original Design for a Knitted Fabric, of which the following is a specification:

My design for a knitted fabric is fully shown in the accompanying photographic illustration.

The design consists of loosely-knitted loops drawn together at certain points *a*, so as to form openings *b*, which are arranged in line with each other, both longitudinally and transversely, and are separated from each other in one direction by open net-work, and in the other direction by closer net-work, all substantially as described, and as shown in the drawing.

I do not desire to claim, broadly, a design consisting of loops drawn together so as to form openings; but

I claim—

The design for a knitted fabric, said design consisting of loops drawn together so as to form openings *b* in line with each other, both longitudinally and transversely, and separated from each other in one direction by open net-work, and in the other direction by closer net-work, all substantially as described, and as shown in the drawing.

In testimony whereof I have signed my name to this specification in the presence of two subscribing witnesses.

HENRY ROOT.

Witnesses:

H. A. TRUITT,
HARRY SMITH.
